UNITED STATES PATENT OFFICE.

OSCAR LEONARD BAXTER, OF COLUMBUS, OHIO.

WINDOW CONSTRUCTION.

1,301,896.

Specification of Letters Patent. Patented Apr. 29, 1919.

Application filed August 27, 1917. Serial No. 188,300.

To all whom it may concern:

Be it known that I, OSCAR LEONARD BAXTER, a citizen of the United States, residing at Columbus, in the county of Franklin and 5 State of Ohio, have invented certain new and useful Improvements in Window Construction, of which the following is a specification.

This invention relates to window construction and is particularly directed to a structure whereby a muntin may be rigidly and easily secured in position. With my arrangement, the window structure may be 10 very cheaply manufactured and the parts 15 readily assembled upon the ground in such manner as to be burglar proof and also to avoid allowing water to enter the interior of the building.

The objects of my invention will become 20 more apparent after a detailed description of the accompanying sheet of drawings in which similar characters of reference designate corresponding parts, and in which:

Figure 1 is a fragmentary perspective 25 shown partially in section of a window frame and muntin in their proper positions,

Fig. 2 is a top plan view of the structure shown in Fig. 1,

Fig. 3 is a fragmentary perspective of a 30 portion of the window frame,

Fig. 4 is a fragmentary perspective of the loose muntin half used by me, and,

Fig. 5 is a fragmentary perspective of the 35 fixed muntin half with the reinforcement member shown in position.

In these drawings, the window frame is designated by the reference numeral 1 and is shown as integrally carrying the fixed stop 2. Opposite the fixed stop, there is located the loose stop 3 which is usually placed 40 on the inside of the building. The fixed stop is also provided with an upstanding lip 4, which is pierced and threaded as shown at 5 for a purpose to be presently described.

This lip is preferably struck out of the 45 metal forming the stop itself and serves as the means for holding the muntin in position. The fixed muntin half is designated by the reference numeral 6, it being understood 50 that this half may be of any preferred shape and be provided with inturned edges 7 projecting toward each other, but also spaced from each other a distance sufficient to permit the passage therethrough of the 55 rib 8 of the reinforcement member 9. The legs 10 of this reinforcement member closely

fit the inside of the sides of the fixed half of the muntin and are so shaped at their lower ends as shown at 11, to wedge the lip 4 between them and the fixed muntin half. 60 I preferably make the parts of a size so that the reinforcement member will wedge into the position shown, whereby it is temporarily held in such position. In fact, this frictional engagement or wedging of the 65 parts in this position may, if desired, be relied on to permanently hold the fixed muntin in position if this is desired. The loose muntin half is designated by the reference 70 numeral 12 and is also provided with inwardly projecting edge portions 13 spaced slightly from each other to permit the entrance of the rib 8, as shown. It is through the loose muntin half that the fastening 75 screw 14 passes, this screw also passing through the reinforcing member 9 and being ultimately threaded into the threaded opening 5 of the struck-out lip 4. By this arrangement, the reinforcement member is 80 permanently and rigidly held in position 85 and likewise shifting or moving of the muntin itself is impossible.

From the foregoing description, it will be apparent that I have provided a structure wherein the muntin may be rigidly and 85 easily secured in position. This is accomplished by cutting out the lower portion of the inturned legs 7 of the fixed muntin half 6, as is shown at 5, whereby this fixed muntin may be readily passed over the lip 4. 90 The reinforcement member is then jammed into position and because of this wedging or frictional hold, will remain in such position. This is primarily intended for the convenience of the workmen assembling the 95 job. After that, the loose muntin half may be placed in position and the screws 14 applied.

What I claim, is:

1. The combination with a window frame 100 provided with an upwardly projecting lip, of a fixed muntin half cut out at its lower inside portion to pass over said lip, a loose muntin half, a reinforcement member fitting within said fixed muntin half provided with a rib 105 projecting beyond said fixed half toward said loose half, said member being of a size to cause said lip to snugly fit between said member and said fixed muntin half, and a screw passing through said loose muntin 110 half, through said member, and into said lip.

2. The combination with a window frame provided with an upwardly projecting lip, of a fixed muntin half cut away at its lower inside portion to pass over said lip, a loose 5 muntin half, a reinforcement member fitting within said fixed muntin half provided with a rib projecting beyond said fixed half toward said loose half, said member having its lower edges substantially double for 10 wedging engagement with said upwardly

projecting lip, and threaded means passing through said loose muntin half, through said member and into said lip.

In testimony whereof I affix my signature in presence of two witnesses.

OSCAR LEONARD BAXTER.

Witnesses:
